UNITED STATES PATENT OFFICE.

JAMES A. SCOTT, OF MONMOUTH, ILLINOIS.

IMPLEMENT FOR CAPPING CARTRIDGE-SHELLS.

SPECIFICATION forming part of Letters Patent No. 363,175, dated May 17, 1887.

Application filed February 23, 1886. Renewed April 20, 1887. Serial No. 235,489. (No model.)

To all whom it may concern:

Be it known that I, JAMES A. SCOTT, a citizen of the United States, residing at Monmouth, in the county of Warren and State of Illinois, have invented new and useful Improvements in Implements for Capping Cartridge-Shells, which improvements are fully set forth in the following specification, reference being had to the accompanying drawing.

10 My invention relates to improvements in which a movable handle or arm operates a toggle-joint in conjunction with a capping-pin, a radial arm, and a stationary collar or socket for holding cartridge-shells; and the objects 15 of my invention are, first, to provide for increasing the amount of power used, transmitting the same to the capping-pin; second, to reduce the friction of the capping-pin. I attain these objects by means of the mechanism 20 illustrated by the accompanying drawing, in which the figure is a view partly in vertical section and partly in elevation.

The handle A, the upright post L, the post E, with its rib-brace I, the shoulders F F, and collar Q constitute the stationary part of the implement. At the upper end of the post E, on the fulcrum-pivot M, works one end of the lever T, which, in connection with the lever C at the common pivot S, forms a toggle-joint. 30 At the lower end of the lever C, by means of the common pivot N, is connected the capping-pin H. The lower end of the capping-pin H passes through the arm A at the hole X. The handle B is but an elongated projection from 35 the side of the lever T, and is bent to conform to the hand of the operator.

It is plain that when the handles A and B are grasped in the hand of the operator and the handle B is forced downward toward the 40 handle A the arms of the toggle-joint T C are brought into a straight line, thereby forcing the capping-pin H downward upon a cap of a cartridge-shell when resting with its breech-rim on the collar Q and the shoulders F F.

One end of the radial arm D is attached to 45 the top of the capping-pin H by means of the common pivot N, the other end working upon the fulcrum-pivot P at the top of the post L, the object of this being to remove all side pressure from the capping-pin H and convey 50 such pressure to the post L, thereby removing all friction that might be occasioned by the capping-pin H pressing against the sides of the hole X when the implement is in operation.

I am aware that prior to my invention implements for capping cartridge-shells have 55 been made with two handles connected by a joint with a capping-pin, and with collar and shoulders in which to place the cartridge-shell. I therefore do not claim such a combination; 60 but

What I do claim for my invention, and desire to secure by Letters Patent, is—

1. The combination, in an implement for capping cartridges, with a handle, A, having 65 downwardly-extending shoulders F, a collar, Q, supported by said shoulders, and a post, E, projecting upwardly from the handle, of a lever, B, having a downwardly-extending lug, T, pivoted to said post, a capping-pin, H, 70 extending through an opening in the handle, and the lever pivoted to the capping-pin and to the lever T, substantially as set forth.

2. The combination, with the handle and means, substantially as described, for supporting a cartridge, of the toggle-joint and its operating-handle, said operating-handle being pivoted to a post, E, extending upwardly from the handle A, a capping-pin pivoted to the lever C of the toggle-joint and extending 75 through an opening in the handle A, and the arm D, pivoted to the capping-pin and to arm L, projecting from the handle, as set forth.

JAMES A. SCOTT.
